J. H. Ransom, of Albany, N. Y.

Letters Patent No. 933. Dated Aug. 25, 1857.

The schedule referred to in these Letters Patent, and making part of the same.

Be it known that I, Samuel H. Ransom, of the City of Albany, State of New York, have produced a new and original ornamental design for the plates of a stove, called by me the Evening Star Stove; and I declare that the annexed delineations, forming part of this specification, are accurate representations of the said plates, which are combined to form the stove with the ornamental parts; the right hand end plate, and the back of the same not represented being symmetrically similar to the left end plate,

and front of the urn, represented.

What I claim as my production and desire to secure by Letters Patent, is the combination and arrangement of ornamental figures and forms represented in the accompanying delineations, forming together the ornamental design for the plates of a stove.
